(57) **CLAIM**

The ornamental design for a circular wedge spacer, as shown and described.

DESCRIPTION

FIG. 1 is a perspective view showing the front, top and right side of a circular wedge spacer which forms my new design; FIG. 2 is a perspective view showing the rear, top and left side thereof;

FIG. 3 is a top plan view thereof;

FIG. 4 is a front elevational view thereof;

FIG. 5 is a rear elevational view thereof;

FIG. 6 is a left side elevational view thereof;

FIG. 7 is a right side elevational view thereof; and,

FIG. 8 is a bottom plan view thereof.

The broken line showing of a circular wedge spacer is for the purpose of illustrating portions of the article and forms no part of the claimed design.
